UNITED STATES PATENT OFFICE

2,421,735

METHOD OF ELECTROLYTICALLY REPRODUCING PRINTS OR DESIGNS

Clarence O. Prest, Burbank, Calif.

Application December 22, 1941, Serial No. 423,997

5 Claims. (Cl. 204—18)

1

This invention relates to a method of reproducing prints or designs from one surface to another, and this application is a continuation-in-part of copending application Serial No. 332,077, filed April 27, 1940, now Patent No. 2,306,082, granted December 22, 1942. It is particularly advantageous in producing reproductions of drawings, designs, templates, dies and the like, in connection with the aircraft or ship building industries wherein by reason of the high degree of accuracy that can be attained by the method large, substantially flat, sheets of metal are used as material upon which master layouts are drafted.

There is a great duplication of work in many industries because of the lack of a simple, cheap and accurate method of reproduction of such metal layout drawings. For instance, in the aircraft industry, the design of a particular part of the aircraft is made by the engineering department who, in turn, transmits such design to the factory for production. The factory or the engineering department usually drafts the part design drawing on the surface of metal sheets to form what is commonly known as the master template layout. This drawing may be made by scribing through a painted surface coating previously applied to the sheet metal by suitable means. In utilizing these master template layouts the factory must necessarily redraft the design usually on similar metal plates which are subsequently cut in order to form the necessary templates, dies, parts and the like means to produce the design on a production basis. Furthermore, several duplicate template copies of each part or tool are usually required and such original design may therefore need to be redrafted a great number of times prior to its actual construction. This redrafting has heretofore been accomplished by hand copying methods similar to that employed for the original layout. Such a method of reproduction is obviously very expensive both from the standpoint of labor and time and also extremely inaccurate due to the possibility of human errors.

The principal object of the invention is, therefore, to provide a novel and improved method of reproduction from such master layouts with a minimum of time and labor and without sacrificing accuracy.

The invention accordingly resides primarily in a method for making such reproductions by means of electrochemical action or by electro-deposition of material from one metal surface to another.

It is also desirable to obtain paper duplicate

2

prints from the metal master layouts for various uses in the engineering work. Heretofore when such paper prints were desired it has been necessary to redraft the drawings upon paper or cloth from which blue prints could be obtained or to resort to photographic methods for copying the metal layout drawings.

A further object of this invention is accordingly, to provide a method which will enable reproduction of the drawings upon paper from the metal layout sheets without the necessity of redrafting, photographing or the like expensive and time consuming operations.

The invention, accordingly, involves a method of making such reproductions directly upon paper, cloth or the like pervious materials from the metal layout sheets.

Further objects, advantages and features of novelty of the invention will be made evident hereinafter.

In the drawings which show diagrammatically and by way of illustration a preferred embodiment of the invention;

Figure I is an elevation, sectional view, showing a simple and preferred form of apparatus wherein the invention may be practiced, such apparatus and the elements constituting this invention being shown in a clearly defined manner by exaggerating the drawing vertically.

Figure II is similar to Figure I except that the press is in operation, resulting in the squeezing of the various elements in close contact with one another prior to and during the reproduction process.

Figure III is a plan view of the apparatus shown in Figure I and Figure II.

Figure IV is a view of a typical design or print laid out on the original surface.

Figure V is the result of the method described in this invention showing the reproduction which has been printed from the original surface of Figure IV in conjunction with the apparatus of Figures I, II and III.

In the apparatus which I have shown in Figures I and II, I employ two cooperating parts 10 and 11 of a suitable hydraulic press or the like apparatus which are adapted to be moved together under pressure, if necessary, and apart to accomplish results which will be hereinafter described. The member 10 may be considered as a support or table and the member 11 may be termed a head or ram which moves relative to the table 10. Both the table 10 and the head 11 of the press may be lined with a resilient or a fluid-like material 12 and 13, such as rubber, linoleum, com-

posite board, or the like. Although it is not necessary that the said lining or pads 12 and 13 be definitely attached to the table 10 and head 11, it is to be understood that the elements must have a relative association substantially that which is shown. The original surface 14 upon which the design is made and the surface 15 on which the design is to be reproduced are inserted between the resilient pads 12 and 13. An electrical connection is made to both surfaces in such a manner that a current is passed between such surfaces. One plate then becomes the cathode and the other the anode. In order to produce as even a current distribution over the surfaces 14 and 15 as is possible, and in order to simplify the electrical problem, I have found it advisable to install oppositely arranged networks 16 and 16' carried on the pads 12 and 13 and preferably constructed of relatively thin strips of a high conductivity material such as terneplate or copper, and to lead the wiring of each to outside terminal posts 17 and 17' to connect them to the electrical source, thus eliminating the necessity of making individual connections to each set of surfaces inserted into the press. The contactor strips of the said network are preferably staggered with respect to one another in order to eliminate any possibility of short-circuits between them in case small surfaces which do not entirely cover the contactor strips of the network are used. Further, it has been found advantageous, and therefore preferable, to install the posts 17 and 17' on opposite sides of the apparatus in order to insure an even distribution of current.

Figure III shows a plan view of the table with the various elements necessary to the invention outlined thereon.

Figure IV shows the original surface 14, in this case being a flat metal plate which has been previously coated, painted or sprayed with an insulating paint or otherwise provided with an insulating coating such as an oxide coating formed in situ thereon and forming an insulating surface 18, thus completely isolating the surface 15 from any possible contact with surface 14 when they are placed together in the press. A design, layout or print 19 which it is desired to reproduce is then scratched, scribed or scored through the insulating surface 18 and into the original metal plate 14. The insulation coating 18 is thus removed along the line of the scratches forming the design 19. The thus scribed metal plate is then wet with a solution or electrolyte 20, preferably ferrous or manganese chloride or sulfate, and squeezed by means of the apparatus into close contact with the surface of an uninsulated plate 15 upon which the reproduction or design is to be made. An electrical current 21 is then applied to the elements 14 and 15 as the anode and cathode respectively, resulting in the formation of the reproduction 22 upon the plate 15.

While aqueous solutions of the ferrous or manganese chlorides or sulfates mentioned above comprise the preferred marking agents, many other materials may be employed. For example, a solution of a salt of substantially any metal which can be deposited electrically, such as iron, copper, zinc, tin, etc., will deposit a film of metal when the sheet to be marked is made the cathode. It is advantageous but not essential for the cation of the salt to be of a differently colored metal than the sheet to be marked. Also, substantially any acid or salt, even of a metal which does not electrolytically deposit, can be employed to carry metal from a marking plate to the plate to be

marked. By making the plate to be marked the anode, similar solutions can be employed to electrolytically etch this plate, or, by using an alkaline solution, the plate to be marked can be subjected to anodic oxidation. In the latter case, alternating current can be employed. Thus, substantially any conducting solution is effective as a marking agent to form a deposit upon or change the appearance of the plate to be marked at portions corresponding to the conducting portions of the master plate so as to transfer the design.

Figure V shows the reproduction 22 of the design 19 which has been formed by means of the invention described herein. It will be noted that by means of an electrolytic action, there has been a visual alteration of the surface of the reproduction plate 15 by etching, oxidation, deposition of metal from the electrolytic solution or transfer of the material from the original surface 14 to the reproduction plate 15.

I have found by my experiments and research that it is possible to insert between the original surface 14, and the reproduction surface 15, a sheet of flexible pervious material 23, such as paper, cloth or any similar fibrous, non-conductive material, without substantially affecting the process. In this manner a print is made on the flexible material 23 as well as on the reproduction plate 15. It is, therefore, possible to not only make a reproduction on the metal surface 15 but it is possible to obtain prints on flexible material such as paper and the like at the same time and during the same operation. This is advantageous in many respects, notably that it produces a record on paper which can be checked prior to further processing the reproduction plate 15. This arrangement is shown in Figure I.

I have also found by experiment and research that by means of certain solutions or electrolytic fluids in association with the apparatus and invention herein described, I can produce a print, similar to the common blue-print, in a simple, cheap and accurate manner. This is accomplished by dipping the paper in a primary solution, preferably of iron and ammonium citrates, due to the cheapness of these substances, or a similar fluid, subjecting it to the electrolytic process of this invention, and then developing in a solution of potassium ferric cyanide. Transfer of material is not necessary in this case. Upon completion, the paper is taken out of the press, washed and dried. This process enables one to print directly from the surface of the metal plate. Furthermore, it enables one to obtain a plurality of prints in one operation, if desired.

As a further example of the adaptation of this process to the making of paper prints direct from the scribed metal plate drawing, it has been found that such paper print may be made by wetting the surface of the said original scribed plate 14 and saturating the paper with a solution of a soluble salt of an organic or non-organic alkali metal salt whose corresponding silver salt is also soluble. The thus saturated paper is then placed between the plate 14 and an opposite plate of silver or a metal plate having this inner contacting surface adjacent the paper coated with a layer of silver, and the whole assembly comprising the two plates and the intermediately positioned paper placed in the press in the position shown at 16, 15 and 23 in Figure I. Pressure is then applied by the press to force the original plate 14 and the silver coated plate 15 in close contact with the intermediate paper 23 as shown in Figure II, and a unidirectional current of ap-

proximately two (2) volts potential difference is then applied to the plates through the terminals 17 and 17¹ for approximately ten seconds. The polarity should be such that the metal plate 14 carrying the design is the cathode while the silver plate 15 is the anode. The resulting electrochemical reaction produces in the paper dark lines of silver oxide corresponding exactly with the contacting scribed design on the original metal sheet 14. The paper may then be removed from the plates in the press and immediately washed and dried without need of developing and fixing. The resultant dark line print may then be used directly or may be employed as a master tracing from which a plurality of blue prints or the like copies can readily be made by the usual contact printing method. In this process the silver oxide is found to be precipitated or electrically deposited in the lines throughout the thickness of the paper which results in an opaque line which is particularly advantageous in obtaining sharp and contrasting duplicate contact prints therefrom.

Examples of some of the metal salts which may be employed in the before described paper printing process are the soluble nitrates and sulfates of the alkali metals, lithium, sodium and potassium, and of the alkaline earths such as calcium and magnesium. Of these the sulfate and especially the nitrate of potassium and sodium are particularly satisfactory. Suitable metal organic salts comprise sodium and potassium acetates.

A similar process may be carried on by employing, instead of silver, an anode plate of copper or any metal below copper in the electromotive series.

It has also been found that this process of making paper prints from scribed metal plates carrying an insulating coating as hereinbefore mentioned may be performed in the manner just described but employing water or a peroxide of hydrogen, sodium, or potassium, or other compound which readily yields oxygen by electrolysis. For example, the surface of the original scribed plate 14 from which a print is desired, and the paper upon which the print is to be made may be wetted with a solution of hydrogen peroxide and the paper then pressed between the said plate 14 and the silver coated plate 15 in the press and the electric potential applied as before described. The resultant electrochemical reaction will produce a black silver peroxide design print upon the paper corresponding to that carried in the scribed insulating coating of the layout plate 14.

It has also been found particularly advantageous to employ an electrolyte solution comprising a mixture of a nitrate and a peroxide such as, for example, equal volumes of an aqueous solution of three percent (3%) hydrogen peroxide and an aqueous solution containing one and one-half (1½) pounds of sodium nitrate per gallon. This electrolytic mixture results in a particularly dense black line in the paper.

A similar process may be carried on by employing, instead of silver, an anode plate of copper or any metal below copper in the electromotive series. An electrolyte of phosphoric acid may also be used in connection with these metals.

While hereinbefore, for convenience of illustration, the reproduction of the design upon paper has been described in connection with this invention, the method is equally applicable to the reproduction of such designs upon cloth sheets

or upon bodies of pulpy or other suitable pervious materials.

While it is ordinarily not necessary to do so, the lines printed upon the paper or cloth in the before mentioned processes, especially those containing silver, may be darkened and rendered more permanent by a supplementary treatment, immediately after printing, with a solution of a sodium sulfide. This treatment is effective in connection with all of the before mentioned metal salt solutions but particularly so when the print has been made with a silver salt solution.

A relatively thin translucent type of vellum tracing paper may be employed in these processes.

15 The processes which I have described herein may be adapted to use with a lofting board. A lofting board is used by many industries in order to sketch up contours, water-lines, etc. in relatively large scale in order to further their manufacturing process. Many times the templates and jigs for the various parts of the ship or airplanes are made from such lofting work. This invention can be applied to such work by means of a portable apparatus which can be taken to the lofting board and prints upon metal, paper or cloth made directly therefrom, or, if preferable, the lofting board can be made in sections, the sections taken up and transferred to the reproduction apparatus to be adapted to the process herein described.

20 It will be apparent that the apparatus and method of the present invention is not limited to the marking or printing on flat surfaces but that a properly formed master marking element can be similarly caused to register with curved or irregular surfaces on the article to be marked and be pressed thereagainst by any suitable means. Also, a marking means can be formed of relatively thin sheet metal and be caused to conform to the surface of an irregularly shaped article by a press of the type illustrated herein.

25 It is to be understood that the description and illustration disclosed herein is merely illustrative of one form which this invention may take and is not to be limiting; other variations and modifications being obviously possible without departing from the scope of the invention and the appended claims.

I claim:

30 1. A method of reproducing a design which comprises forming a layer of insulation upon the surface of a first member of electrically conducting material which constitutes a cathode, removing portions of said insulation and thereby exposing the surface of said electrically conductive material in an outline corresponding to the form of said design, transferring said design to the surface of a second member by wetting said second member with a solution of an alkali metal salt of the group consisting of the nitrates, sulfates, and acetates of the alkali metal, said second member being of non-conductive, fibrous material and being pervious to said solution, pressing said second member containing said solution between the surface of said first member 35 carrying the design and a third member constituting an anode and having a silver surface of contact with said second member, and passing an electric current through said second pervious member between said first and third members at the points where said insulating layer is removed from said first member.

40 2. A method according to claim 1 in which the said second member of pervious material is a paper sheet.

45 3. A method according to claim 1 in which said

second member of pervious material is a cloth sheet.

4. A method according to claim 1 in which the alkali metal salt is sodium nitrate.

5. A method according to claim 1 in which the alkali metal salt in said solution is sodium nitrate and in which said solution contains hydrogen peroxide.
